UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LAMBREQUIN.

SPECIFICATION forming part of Design No. 14,621, dated February 5, 1884.
Application filed December 26, 1883. Term of patent 3½ years.

To all whom it may concern:

Be it known that I, JOHN QUINCY REED, of the city, county, and State of New York, have invented and produced a new and original 5 Design for a Pattern for a Mantel-Lambrequin, (numbered 9,022;) and I do hereby declare that the engraved prints accompanying this specification convey to any one accustomed to using paper patterns a clear understanding of how to a garment made up by the pattern will appear.

The design shows a plain lower portion and a longer and wider upper portion that displays a draping at the center and near each

end. The upper portion shapes two festoons 15 over the lower portion, and displays two ends falling some distance below the sides of the lower portion.

What I claim as my invention, and desire to secure by Letters Patent, is—

The design for a mantel-lambrequin, as shown in the engraved prints accompanying this specification.

JOHN QUINCY REED.
